(57) **CLAIM**

The ornamental design for a chair, as shown and described.

DESCRIPTION

FIG. 1 is a front elevation view of a chair, showing our new design therefor;

FIG. 2 is a rear elevation view thereof;

FIG. 3 is a right side elevation view thereof;

FIG. 4 is a top plan view thereof;

FIG. 5 is a bottom plan view thereof; and,

FIG. 6 is a perspective view thereof.

The left side view of each embodiment is a mirror image of the right side view, and hence is not depicted.

The mesh of the part depicted in black of a seat shows the portion to which texture is fine rather than other parts.
